(57) **CLAIM**

The ornamental design for a cowling for four-wheeled motorcycle, as shown and described.

DESCRIPTION

FIG. 1 is a top perspective view of a cowling for four-wheeled motorcycle showing our new design;

FIG. 2 is a right side view thereof;

FIG. 3 is a left side view thereof;

FIG. 4 is a front side view thereof;

FIG. 5 is a rear view thereof; and,

FIG. 6 is a top plan view thereof;

The bottom of the cowling is not shown in the drawing and forms no part of the claimed design.
